THREAD GUIDE FOR STRAIGHT KNITTING MACHINES

John O. Wrightson, Philadelphia, Pa., assignor to
 Arcadia Hosiery Co., Lansdale, Pa., a corpora-
 tion of Pennsylvania

Application October 2, 1934, Serial No. 746,607

5 Claims. (Cl. 66—126)

This invention relates to thread carriers for knitting machines and particularly those used on flat machines of the type commonly employed in the manufacture of full fashioned hosiery.

5 The object of this invention is to provide a thread guide which will not injure the sinkers of the knitting machine nor will itself become injured as a result of the motion for effecting needle-traversing movement of the thread guide getting out of time with the motion which projects the sinkers of the machine outwardly across the path of the thread guide, i. e. in cases where the sinkers are projected in advance of the thread guide instead of behind the thread guide as the 10 thread guide is moved in opposite directions alternately in a plane parallel to and intermediate that of the front ends of the sinkers and the plane of the bank of needles with which the sinkers cooperate.

20 This invention is particularly adaptable for use with the recently developed three-carrier knitting process, adapted for eliminating rings in sheer hosiery, wherein each of the three individual thread carriers employed makes but a single needle-traversing movement at any one time, which requires the disconnection of each carrier rod from the Coulier motion of the machine or a friction box driven by said motion after the thread guide has laid thread for one course of 25 stitches and the reconnection of a different carrier rod to the mechanism which effects the needle-traversing movements of the thread guides before a thread is laid to the needles for the formation of a succeeding course of stitches. 30 This recurrent connecting and disconnecting of the thread bars or carrier rods frequently causes one or more of the thread guides to be moved out of time with the slur cock, also driven by the Coulier motion, by which the sinkers are projected 35 across the path of the thread guide.

With the usual rigid thread guide, the projecting of a sinker in advance of the thread guide instead of behind the thread guide results in damage to either the thread guide, the sinkers, or both and most often to the sinkers, which are of a more or less delicate construction.

40 The thread guide constituting the subject matter of the present invention is so constructed that, 45 in event of the lower end of the thread guide contacting with any one of the sinkers in the course of travel of the thread guide across the series of sinkers, such contact will result in the lower end of the thread guide being moved laterally to an inoperative position above the tops of 50

the sinkers without damage being done to either the thread guide or the sinkers.

Alternating with the sinkers is a series of dividers which are of substantially the same construction as the sinkers and which are projected 5 outwardly between the sinkers, after the sinkers have been successively projected, in order to divide the thread equally around and between each and all of the needles then operating in any single knitting head of the machine. 10

During certain parts of the knitting operation the sinkers and dividers are operated en masse by the catch bar of the machine and if for any reason one or more of the sinkers or dividers shall fail to be retracted by the catch bar and be left in 15 a projected position until the thread guide makes its next needle-traversing movement the thread guide will upon engaging the projected divider or sinker be moved to the inoperative position above noted, thereby avoiding damage to either the 20 sinkers, dividers, or the thread guides by any improper relation of the elements at such time.

In the accompanying drawings:

Fig. 1 is a front elevation of the preferred form of the invention, showing the thread guide in 25 operative relation to the carrier rods and the sinkers and dividers of a flat knitting machine;

Fig. 2 is a transverse sectional elevation taken on the line 2—2, Fig. 1;

Fig. 3 is an enlarged transverse sectional elevation taken on the line 3—3, Fig. 1; 30

Fig. 4 is a view similar to Fig. 1 illustrating a modified form of the invention;

Fig. 5 is a transverse sectional elevation taken on the line 5—5, Fig. 4; 35

Fig. 6 is an enlarged transverse sectional elevation taken on the line 6—6, Fig. 4; and

Fig. 7 is a sectional elevation taken on the line 7—7, Fig. 6.

In Figs. 1, 2, 4 and 5 of the drawings, three of the carrier rods of an ordinary full-fashioned hosiery knitting machine are illustrated at 1, 1. Normally these machines are provided with seven such carrier bars and in the above noted three-carrier method of knitting three of the bars are 45 used in predetermined order for respectively laying individual threads controlled thereby between the needles and sinkers of the machine.

The sinkers of the machine are illustrated at 2, 2 which, as shown in Figs. 1 and 4, alternate 50 across the machine with the dividers 3, 3. The sinkers are normally projected outwardly across the path of movement of the thread carriers from the full line to the broken line positions shown in Figs. 2 and 5, by individual jacks 4 which are 55

successively rocked to effect projection of the sinkers, behind the thread guide as the thread guide advances across the knitting head, by a slur cock illustrated at 5.

5 Each of the thread carrier rods 1 is provided with a thread guide unit 10 and each unit 10 comprises a thread guide holder 11 which is secured to a carrier bar 1, as by screws 12. Normally the thread guide unit comprises a single rigid element secured to the holder 11, as by screws 13, such rigid element comprising a more or less delicate thread-guiding tube 14 at its lower end which is adapted to move past the front shoulder edges 15 of the sinkers and dividers 2 and 3, above 10 the top edges 16 of the thread supporting tongues 17 of said sinkers and dividers and below the top edges 18 thereof, in view of which it will be readily seen that should any one of the sinkers or dividers be disposed in the broken line position of 15 Figs. 2 and 5 when the rigid lower member of the thread guide unit is moving across the sinker bed damage will be done to either one or the other or both of the elements, usually to the more delicate sinker or divider and frequently to the 20 thread-guiding tube 14. Such a condition necessitates the shutting down of the machine for some time to repair the damage, which means the interruption of the knitting operation in anywhere from eighteen to twenty-four stockings 25 which are being simultaneously produced on the machine.

A thread guide made in accordance with the principles of the present invention, instead of being of a rigid nature from the holder 11 to the 30 tube 14, is composed of two pivotally connected members 20 and 21 respectively, the first of which is rigidly secured to the holder 11 by the screws 13 while the latter is pivotally connected to the former as by a screw, rivet, or other equivalent 35 element 22, in order to provide for the pivotal support of the lower member 21.

In the preferred form of the invention the upper member 20 is illustrated as being offset at 40 23, in order that the two elements 20 and 21 may be disposed in substantially the same plane. The pivot element 22 is rigidly secured in a longitudinally extending projection 24 of the upper member 20 disposed below the offset 23.

Normally the upper and lower members 20 and 50 21 are longitudinally aligned one with the other and in order to maintain this normal alignment between the pivotally connected parts, against the normal tension of the thread as placed thereon by the sinkers 2 moving out behind the thread 55 guide and pressing the thread between the needles, the lower part 21 of the unit 10, in the present instance, is provided with a spring-pressed detent comprising in the preferred form of the invention a resilient tongue 25 which extends upwardly beyond the offset 23 of the upper part 20 in overlapping relation to and in contact with said upper member 20. The resilient tongue 25 is provided with a detent 26 which normally lies in a spot depression 27 formed in the upper 60 member 20 of the thread guide unit 10.

The resilient tongue 25 in the present instance is secured to the lower member 21 of the thread guide unit 10 by screws 28, 28 respectively located at opposite sides of the pivot 22 longitudinally of 70 the unit 10.

The depth of the depression 27 is just enough to maintain alignment of the members 20 and 21 under normal thread tension and in event of the tube 14, which is carried by the lower part of the 75 lower member 21 of the thread guide, or any other

portion of the lower part of the thread guide adjacent the tube 14, striking an abnormally projected sinker or divider the lower member 21 will swing about the pivot 22 from the normal full line position shown in Figs. 1 and 4 to either of the 5 broken line positions x or x' illustrated in said figures, depending upon the direction in which the thread guide happens to be moving at the time, in which case in the form of the invention shown in Figs. 1, 2 and 3 the spring-pressed detent 26 will ride out of the depression 27 to a position beyond one or the other of the side edges 29, 29 of the upper member 20 of the thread guide, thereby retaining the lower member 21 of the thread guide in the inoperative position x or 15 x' to which it has been moved.

In that form of the invention shown in Figs. 4, 5, 6 and 7, the resilient tongue 25 on the lower portion 21 and the rigid tongue on the upper portion 20 of the thread guide unit are eliminated 20 and the two parts 20a and 21a which correspond respectively to the members 20 and 21 of the thread guide, instead of being mounted in a common plane, are mounted in immediately adjacent planes. 25

The upper edge 30 of the lower member 21a of the thread guide, as clearly shown in Fig. 7, is formed on an arc swung from the axis of the pivot screw 22a, by which the members 20a, 21a 30 are pivotally secured together.

Secured to the upper member 20a of the thread guide immediately above the upper edge 30 of the lower member 21a thereof is a housing 31 for a modified form of spring-pressed detent 26a. In this case the spring-pressed detent is in the form of a beveled lower end 33a of a plunger 32 slidably mounted in the housing 31 and adapted normally to rest in a central V-shaped notch or depression 34 forming in the rounded edge 30 of the lower member 21a of the thread guide, said 40 detent being resiliently held in said notch by a compression spring 25a mounted in the housing 31 behind the plunger 32.

The housing 31 in the present case is of a sheet metal construction having flanges 36, 36 resting 45 against the under surface of the member 20a and secured thereto by any suitable means such as rivets 37, 37.

The operation of the modified form shown in Figs. 4 to 7 inclusive is substantially the same as 50 that of the preferred form shown in Figs. 1 to 3 inclusive, and when the lower member 21a is swung into either of the inoperative positions x or x' the detent 26a is forced out of the central V-shaped notch 34 and enters one or the other of a pair of laterally spaced notches 29a, 29a formed in the upper rounded edge 30 of the lower member 21a of the thread guide, whereby the said lower member is maintained in said inoperative position, until manually restored to the 60 normal operating position in longitudinal alignment with the upper member 20a of the thread guide, in the same manner as the lower member 21 is held in inoperative relation to the upper member 20 in the preferred form of the invention, 65 by the spring-pressed detent 26 engaging one of the side edges 29 of the upper member 20.

I claim:

1. The combination of a series of sinkers, a thread guide, means effecting relative movement 70 between the sinkers and the thread guide transversely thereof, means pivotally supporting said thread guide on said movement effecting means, means resiliently maintaining the thread guide normally in thread-laying relation to the sinkers 75

and permitting rearward movement of the guide in either direction of travel upon engagement with a sinker, and means maintaining said thread guide in an inoperative position relative to the sinkers resulting from pivotal movement of the thread guide relative to said movement effecting means by contact of the thread guide with one of said sinkers.

5. 2. A knitting machine thread guide comprising an upper rigidly mountable member, a lower member pivotally mounted on said upper member, and a resilient tongue on one of said members overlapping and contacting with the other of said members, a detent on the resilient tongue normally pressed thereby into a depression in said overlapped member for maintaining said members resiliently in normal thread-laying relation to each other or engageable with a side edge of said overlapped member to retain said 10 members in inoperative relation upon relative pivotal movement between said members.

15. 3. A knitting machine thread guide comprising a pair of pivotally connected members, a rounded end on one member and provided with circumferentially spaced peripheral notches, and a spring-pressed detent carried by the other of said members engageable with the peripheral notches of the other member for maintaining said members in either a normal thread-laying relation 20 to each other or in inoperative relation to each other upon relative pivotal movement between said members.

30. 4. A yarn carrier for use in straight knitting

machines having a plurality of movable sinkers and provision for reciprocating the yarn carrier to lay yarn along said sinkers, said yarn carrier comprising an upper rigidly mountable member, a lower member pivotally attached to said upper member, and a spring pressed detent carried by one of said members and entering a depression in the other of said members normally maintaining said members resiliently in normal thread laying relation one to the other and permitting rearward movement of the lower member in either direction of travel upon engagement with a sinker.

10. 5. A yarn carrier for use in straight knitting machines having a plurality of movable sinkers and provision for reciprocating the yarn carrier to lay yarn along said sinkers, said yarn carrier comprising an upper rigidly mountable member, a lower yarn laying member pivotally mounted on said upper member for rearward movement from the normal yarn laying position in either direction of travel, a resilient tongue on one of said members overlapping the other of said members, and cooperating means on said tongue and said overlapped member respectively for resiliently maintaining said members in normal thread-laying relation to each other to permit said rearward movement of the yarn laying member upon engagement with a sinker or in inoperative relation upon relative pivotal movement between said members.

JOHN O. WRIGHTSON.
